UNITED STATES PATENT OFFICE.

ESSINGTON N. GILFILLAN, OF CHICAGO, ILLINOIS; EMMA GILFILLAN EXECUTRIX OF
SAID ESSINGTON N. GILFILLAN, DECEASED.

EGG CARRIER OR RECEPTACLE.

1,029,749.

Specification of Letters Patent. Patented June 18, 1912.

Application filed July 15, 1908. Serial No. 443,603.

To all whom it may concern:

Be it known that I, ESSINGTON N. GILFILLAN, a citizen of the United States, residing at Chicago, in the county of Cook and State 5 of Illinois, have invented certain new and useful Improvements in Egg Carriers or Receptacles, of which the following is a specification.

This invention relates to improvements in 10 egg carriers or receptacles, and the primary object of the same is to provide an improved, simple, durable and inexpensive device of this character which is adapted to be collapsed and shipped in a knocked down 15 condition.

A further object is to provide an improved device of this character comprising a flexible body portion adapted to be bent into shape, and improved means for holding 20 the parts in position for use.

A further object is to provide improved means for dividing the body portion into the desired number of compartments.

A further object is to provide improved locking and dividing strips for the body portion, and improved means for holding 25 said strips against accidental displacement.

To the attainment of these ends and the accomplishment of other new and useful objects as will appear, the invention consists 30 in the features of novelty in the construction, combination and arrangement of the several parts hereinafter more fully described and claimed and shown in the accompanying drawings illustrating an embodiment of the invention, and in which—

Figure 1 is a top plan view of an improved device of this character constructed in accordance with the principles of this invention. Fig. 2 is a plan view showing the body portion in a knocked down condition for shipment. Fig. 3 is a sectional view on line 3—3 of Fig. 1, showing two of these receptacles connected together and coöperating 40 to form a closed receptacle or carrier. Fig. 4 is a detail perspective view of the locking and dividing strips for holding the body portion in position for use. Fig. 5 is a plan view of a portion of a modified form of the blank, and Fig. 6 is a view similar to Fig. 3, showing the modification.

Referring more particularly to the drawing, and in the present exemplification of the invention, the numeral 10 designates the body portion of the receptacle which may

be constructed of any desired or suitable material, such as card board, or the like. This body portion may be of any size and configuration, according to the size of the receptacle it is desired to construct, and is 60 preferably rectangular in configuration. The body portion is provided along two diametrically opposite edges with spaced slots 11, which open outwardly through the edges of the body, and the slots in one edge are 65 arranged in line with the slots in the opposite edge. The body portion is also provided with a plurality of slots 12, arranged within the edges of the body portion and in line with the slots 11 in the edges of the 70 body. These intermediate slots 12 are preferably spaced from each other to form parallel rows and are also spaced from the slots in the respective adjacent edges. Any number of these slots 11 may be provided, accord- 75 ing to the number of compartments into which it is desired to divide the receptacle, and any number of slots 12 may be provided, according to the number of partitions it is de- 80 sired to form in the body. The blank thus formed and comprising the body portion 10 is adapted to be bent to form partitions 13, which extend entirely across the body portion and are parallel with the edges of the blank. In the present exemplification of 85 the invention, the blank is provided with two rows of slots 12 to form two partitions 13, and the body portion is provided with creases 14 which intersect the slots 12, said creases adapting the material to form the 90 partitions 13 and when so bent, the lower edges of the slots 12 will be substantially in line with each other below the edge of the partition, and will open through the top of 95 the respective partitions. The edges of the body portion in which the slots 11 are located are also bent, as at 15, to form side walls which are spaced from and are parallel with the respective partitions 13, and the walls 15 are of such a height that the 100 slots 11 therein will register with the slots 12 and the bottom of the slots will be located in substantially the same plane as the bottom of the slots 12. Suitable locking strips 16 may be provided for holding the body portion in position when thus bent. These strips may be constructed of any suitable material, but are preferably constructed of the same material of which the body portion 10 is constructed, and are of a height 105 110

substantially equal to the height of the slots 12 when the body portion is bent into the position shown in Figs. 1 and 3, so that when the locking strips 16 are placed in position to extend transversely across the body portion 10 and to rest in the respective alined slots 11, 12, the upper edge of the locking strip will be substantially flush with the upper edge of the partitions 13 and the side walls 15. When the body portion is shaped as shown in Fig. 3, the slots terminate at some distance above the bottom of the receptacle thus formed, and when the locking strips 16 are in position, the lower edges thereof will be supported above the bottom of the receptacles by resting upon the bottom of the slots 11, 12.

The locking strips 16 may be held against longitudinal displacement with respect to the body portion in any desired or suitable manner, and for this purpose the strips may be provided with recesses 17 which extend transversely thereacross. These recesses 17 are arranged in each face of the strips 16 to form a thin division wall 18, which wall is of a width substantially equal to the width of the slots 11, 12. Each of the strips 16 is provided with coöperating recesses 17 for each of the partitions 13 and the side walls 15, so that when the strips 16 are placed in position with the respective partitions 18, located within their respective slots 11, 12, the shoulders 19 formed by the recesses 17 will stand on opposite sides of the partitions 13 and the side walls to hold the strips 16 against longitudinal displacement. Obviously, the recesses 17 which stand adjacent the partitions are of a width greater than the width of the recesses adapted to receive the walls 15. Any number of these locking strips 16 may be provided for dividing the spaces between the partitions 13, and the side walls 15, into any desired number of compartments, and in the present exemplification of the invention, five of such strips are provided which coöperate with the side walls and two partitions 13 for dividing the receptacle or carrier into twelve compartments, two of the strips 16 serving to form end walls of the receptacle.

When it is desired to collapse the receptacle, all that is necessary is to remove or detach the locking strips 16 from the body portion, after which the latter may be stretched out into a flat form, as shown in Fig. 2, so that any number of these receptacles may be shipped in a compact space in a collapsed form to the user, who may assemble the parts to form the receptacles in the manner set forth.

If desired, two of such receptacles may be connected together by a suitable connecting device 20, which may be of any desired construction, and this device 20 is adapted to engage one of the walls 15 of two sections,

so that the sections may be hinged together after they have been shaped and locked in position by the strips 16. The two sections thus assembled may be opened and the eggs placed within one of the receptacles, after which the other receptacle may be closed upon the lower receptacle in the manner shown in Fig. 3 of the drawing, so that one of the sections will serve as a cover for the other section.

Obviously, the connecting or fastening device 20 may be dispensed with, and one of these receptacles loosely placed upon the top of another, in which event they will be held from displacement with respect to each other by the eggs within the compartments, which project into both of the coöperating compartments. It is also to be understood that the grooves or recesses 17 may also be formed in any desired or suitable manner.

There are, of course, many ways in which the top and bottom members of the egg carrier may be joined or hinged, where such hinging is desired. Another way is illustrated in Fig. 6, and consists in making the top and bottom blanks in one piece. When this is done, however, it is desirable to provide the combined blanks at their line of conjunction with an offset bend 20^a, which not only constitutes the hinge upon which the top and bottom members of the carrier turn relative to each other, but which forces these members away from one another when they are opened, and thereby prevents the protruding ends of the strips or partitions 16 from interfering with the opening movement. In order that the strips may be inserted in their respective slots 11, notwithstanding the presence of the shoulders 19 at the ends thereof, the slots are made as shown in Fig. 5 with enlargements 11^b which join the two adjacent slots 11^a in the extreme edges of the top and bottom sections of the carrier, these enlargements 11^b allowing the shoulders 19 at the ends of the strips to pass through the outward bend 20^a when the strips are being inserted.

In order that the invention might be fully understood the details of the foregoing embodiment thereof have been thus specifically described, but

What I claim as new is:

1. A device of the class described comprising a single piece of flexible material bent to form the parallel walls and partitions of an egg carrier, said walls and partitions being provided with slotted edges, said slots being alined transversely to said walls and partitions, and fastening strips removably seated in said slots, said strips being of a thickness greater than the width of the slots and provided with grooves adapting them to be inserted edgewise into said slots.

2. A device of the class described com-

prising a single piece of material provided with creases to form the bottom and side walls of a receptacle, and a plurality of partitions intermediate of said side walls, each 5 of said partitions comprising two spaced walls provided with a plurality of slots in the edges thereof, and fastening devices extending transversely of the receptacle, said devices being of thickness greater than the 10 width of the slots and transversely grooved to fit said slots for locking the parts in position and for dividing the receptacle into a plurality of compartments.

3. A device of the class described, made 15 of a sheet of flexible material provided with folding creases whereby it is adapted to form an egg carrier in sections, each of said sections comprising walls and partitions for separating the eggs, said partitions and walls

being provided with slots opening from the 20 edges thereof, fastening strips of a thickness greater than the width of the slots and provided with grooves adapting them to be inserted edgewise into said slots, the portions 25 of said sections forming said offset bend being provided with enlarged openings communicating with the slots adjacent thereto to permit the passage of the ends of said fastening strips.

In testimony whereof I have signed my 30 name to this specification, in the presence of two subscribing witnesses, on this 11th day of July A. D. 1908.

ESSINGTON N. GILFILLAN.
